US0D1037469S

(12) United States Design Patent (10) Patent No.: US D1,037,469 S
(45) Date of Patent: * Jul. 30, 2024

(54) ISOLATION TANK FOR RELAXATION

(71) Applicant: Kirami Oy, Sastamala (FI)

(72) Inventor: Mika Rantanen, Rymättylä (FI)

() Term: 15 Years

(21) Appl. No.: 35/517,082

(22) Filed: Apr. 18, 2023

(80) Hague Agreement Data

Int. Filing Date: Apr. 18, 2023

Int. Reg. No.: DM/228523

Int. Reg. Date: Apr. 18, 2023

Int. Reg. Pub. Date: May 5, 2023

(51) LOC (14) Cl. 24-01

(52) U.S. Cl.

USPC D24/204

(58) Field of Classification Search

USPC D24/201, 202, 203, 204, 205, 206;
